UNITED STATES PATENT OFFICE.

EDWIN B. STIMPSON, OF BROOKLYN, NEW YORK, ASSIGNOR TO EDWIN B. STIMPSON COMPANY, OF BROOKLYN, NEW YORK.

RIVET-SETTING MACHINE.

Application filed June 16, 1921. Serial No. 477,967.

To all whom it may concern:

Be it known that I, EDWIN B. STIMPSON, a citizen of the United States, residing at Brooklyn, in the county of Kings and State 5 of New York, have invented certain new and useful Improvements in Rivet-Setting Machines, of which the following is a specification.

This invention relates to machines for setting rivets or the like in leather or other sheet material, such machines including, as usual, a hopper, and a raceway down which rivets are fed to a cut-off and transfer slide which delivers them one by one to a pocket 10 or holder whence the individual rivet is driven through a sheet of leather or other material. In such machines the lower end of the raceway has generally been made by affixing strips of steel to the outer face of 15 a stationary part fast to or integral with the machine head, with a unitary nose-piece fast to the inner face of the stationary part, having a rivet-guiding groove non-alined with the main raceway, the nose-piece having another groove extending horizontally 20 and intersecting the rivet-guiding groove, and a slide in the horizontal groove adapted to be moved into alinement with and to receive a single rivet from the raceway proper, and then to be moved into alinement with 25 and transfer the rivet to the rivet-guiding groove of the nose, whence the rivet drops into the carrier, immediately below a driver or plunger.

It is an object of my invention to simplify 30 and improve the structure of machines of the kind referred to by supporting the slide on the nose-piece and between the latter and the stationary member; by making the nose-piece that is attached to the stationary member in two parts, separately secured to the stationary member and with opposed faces 35 grooved to receive and guide a rivet in its descent from the rivet-guiding groove of the slide to the carrier whence it is driven by the plunger; and by providing cooperating parts in the stationary member and in the slide whereby the slide is held in position 40 and restrained to a limited reciprocatory movement, and whereby the endwise removal

of the slide may be permitted without necessitating the removal of any other parts or their fastening devices.

Other objects and aims of the invention, more or less broad than those stated above, 55 together with the advantages inherent, will be in part obvious and in part specifically referred to in the course of the following description of the elements, combinations, arrangements of parts, and applications of 60 principles constituting the invention; and the scope of protection contemplated will appear from the claims.

In the accompanying drawings, which are to be taken as part of this specification, and 65 in which I have shown merely a preferred form of embodiment of invention,

Figure 1 is an elevation of a rivet-setting machine embodying my invention, only such parts being illustrated as are necessary to 70 an understanding of the invention;

Figure 2 is a view similar to Figure 1, but taken at right angles thereto;

Figure 3 is an enlarged detail, partly 75 in section and partly in elevation, illustrating the parts adjacent the carrier, and their relations;

Figure 4 is a detail elevation illustrating the faces of the nose parts adjacent the driver; 80

Figure 5 is a sectional view, enlarged, taken on the line 5-5 of Figure 4;

Figures 6 and 7 are perspective views of the nose-pieces, detached;

Figure 8 is a collective view of the parts 85 of the slide detent;

Figure 9 is a top plan view of the slide, detached;

Figure 10 is a plan view of the same taken 90 at right angles to the view of Figure 9;

Figures 11 and 12 are sectional views taken, respectively, on the lines 11-11 and 12-12 of Figure 9; and

Figure 13 is an enlarged elevation, with parts broken away, showing the outer face 95 of the lower end of member 16 and the relation thereto of detent 30, and slide 27.

Referring to the numerals on the drawings, and first to Figures 1 and 2, numeral 14 indicates the machine head, in 100

which slides a driver 15, actuated by suitable connections which it is not necessary here to show. Another stationary part of the machine, in which the stationary raceway proper is formed, is indicated at 16, and at the upper end thereof is a hopper 17 whence rivets or the like are discharged into the raceway.

The upper section of the raceway consists of strips 18 fastened by screws to the outer face of stationary member 16, while the lower part comprises two cooperating plate sections 19, each having an attaching portion 20 whereby it is secured to the inner face of stationary member 16, and a nose-portion 21 which has a shelf 22 that lies beneath the lower end of stationary member 16. Plate sections 19 are fastened in position by screws with the opposing edges of their nose-portions spaced apart, and in these opposed edges are formed grooves 24 non-aligned with main raceway 18, which together constitute a guideway for the head of a rivet, the shank of the rivet passing in the space between the edges. Because there are two plate-sections the machining of the grooves 24 is a very simple matter, and by regulating the spacing of the sections, rivets of different sizes or diameters of heads may be accommodated. It will be understood that the lower ends of grooves 24 open adjacent the lower end of driver 15, the rivets passing down the grooves and into pocket 25. In the lower end or face of stationary member 16 there is a seat 26 for a slide 27 having a rivet-guiding groove 28 extending through it transversely of its length, the lower edge of the slide moving on the shelves 22 of the nose-pieces 21, and one longitudinal face of the slide projecting to the outside between the lower end of member 16 and the adjacent nose-pieces 21. Reciprocation of the slide (by means not shown) moves it in one direction to register its rivet-guiding groove 28 with the main raceway 18 of stationary member 16, whereby a rivet may drop from the main raceway into the groove 28. This groove 28 is capacitated to take one rivet at a time, and movement of the slide in the opposite direction registers the groove 28 with the guideway formed by the grooves 24 of the sectional plates 19, so that the rivet passes down and into the carrier 25 which, in the operation of the machine, brings the rivet into contact with the sheet of material into which it is to be driven, whereupon downward movement of the driver forces the rivet into the sheet and sets it, the carrier opening in a familiar manner to release the rivet.

In order to hold the slide 27 against endwise withdrawal and to limit its reciprocatory movements in both directions to those positions in which its rivet groove 28 regis-

ters with either the raceway 18 or the grooves 24, I prefer to employ an internally threaded tubular member 29 set in the stationary member 16 from the outer face thereof, having on one (the outer) end a detent finger 30 that normally lies in a seat formed in the outer face of member 16, preventing rotation of tubular member 29, and has its lower end projecting into a cut-out portion 31 in the outwardly projecting longitudinal face of slide 27 (Figures 2, 5 and 13), a screw 32 entering the threaded member 29 from the inner face of stationary member 16, this screw 32 having a flange 33 which is held in position against the inner face of member 16, while permitting of its rotation, by means of a set screw 34 entering into the inner face of member 16, and bearing against flange 33. If screw 32 be turned the result will be to move detent 30 into or out of its seat in the outer face of member 16, and into and out of the cut-out 31. When the detent is moved entirely out of the cut-out 31 the slide 27 may be withdrawn endwise, but without necessitating the removal of any other parts or their fastenings.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the invention which, as a matter of language, might be said to fall therebetween.

I claim:

1. In a machine of the kind described, a stationary member having a downwardly extending main raceway on its outer face and terminating at the lower end thereof in a nose, said nose consisting of two plates fastened to the stationary member with their edges spaced apart and formed with grooves in which the head of a rivet may be accommodated with its shank passing in the space between the plates, the space between said plates being variable to accommodate rivets of different sizes, a riveting plunger mounted to operate in as close adjacency to the delivery end of said grooves as the space between the plates permits, said grooves in said plates being out of registry with the main raceway, and a slide in the lower end of the stationary member movable between the lower end of the stationary member and the plates, having a rivet-guiding groove extending therethrough transversely of its length adapted

to register either with the raceway or with the grooves in the spaced plates, as the slide is moved in one direction or the other.

2. In a machine of the kind described, a stationary member having a downwardly extending main raceway on its outer face and terminating at the lower end thereof in a nose, said nose consisting of two plates fastened to the inner face of the stationary member with their edges spaced apart and formed with grooves in which the head of a rivet may be accommodated with its shank passing in the space between the plates, the space between said plates being variable to accommodate rivets of different sizes, a riveting plunger mounted to operate in as close adjacency to the delivery end of said grooves as the space between the plates permits, said grooves in said plates being out of registry with the main raceway, and a slide in the lower end of the stationary member movable between the lower end of the stationary member and the plates, having a rivet-guiding groove extending therethrough transversely of its length adapted to register either with the raceway or with the grooves in the spaced plates, as the slide is moved in one direction or the other, the outwardly projecting longitudinal face of the slide having a cut-out, and a detent carried by the stationary member and extending into the cut-out, said detent being movable into and out of the cut-out, and means for moving the detent and for holding it on the stationary member in either of the positions to which it may be moved.

3. In an apparatus of the kind described, a raceway member provided with non-aligned rivet-guiding portions, a transfer and cut-off slideable in the member and having a longitudinal surface exposed throughout its length at the outside of the member, said exposed surface of the slide having spaced stop portions, and a detent carried by the raceway member and movable to two positions, in one of which it is in the path of the stop portions of the slide to limit the sliding movement thereof, and in the other of which it clears said stop portions.

4. In an apparatus of the kind described, a raceway member provided with non-aligned rivet-guiding portions, a transfer and cut-off slideable in the raceway member and having a longitudinal surface provided with spaced stop portions exposed at the outside of the raceway member, a detent having a threaded part extending into the raceway member and movable into and out of the path of movement of the said stop portions, a rotary member carried by the raceway member and in threaded engagement with the threaded part of the detent, and means to prevent bodily movement of said rotary member.

5. In a machine of the kind described, a stationary member having a downwardly extending main raceway on its outer face and terminating at the lower end thereof in a nose, said nose consisting of two plates fastened to the inner face of the stationary member with their edges spaced apart and formed with grooves in which the head of a rivet may be accommodated with its shank

passing in the space between the plates, said grooves being out of registry with the main raceway, and a slide in the lower end of the stationary member movable between the lower end of the stationary member and the plates, and having a longitudinal face projecting at the outer face of the stationary member, having a rivet-guiding groove extending therethrough transversely of its length adapted to register either with the raceway or with the grooves in the spaced plates, as the slide is moved in one direction or the other, the outwardly projecting longitudinal face of the slide having a cut-out, and a detent carried by the stationary member and extending into the cut-out, said detent being movable into and out of the cut-out, and means for moving the detent and for holding it on the stationary member in either of the positions to which it may be moved.

6. In a machine of the kind described, a stationary member having a downwardly extending main raceway on its outer face and terminating at the lower end thereof in a nose, said nose consisting of two plates fastened to the inner face of the stationary member with their edges spaced apart and formed with grooves in which the head of a rivet may be accommodated with its shank passing in the space between the plates, said grooves being out of registry with the main raceway, and a slide in the lower end of the stationary member movable between the lower end of the stationary member and the plates, and having a longitudinal face projecting at the outer face of the stationary member, having a rivet-guiding groove extending therethrough transversely of its length adapted to register either with the raceway or with the grooves in the spaced plates, as the slide is moved in one direction or the other, the outwardly projecting longitudinal face of the slide having a cut-out, and a detent carried by the stationary member and extending into the cut-out, said detent being movable into and out of the cut-out, the detent comprising an internally threaded tubular member passing through the stationary member with a head and a finger resting non-rotatively against the outer face of the stationary member, a screw entering the tube from the inner face of the stationary member with a flange resting rotatively against the inner face of the stationary member, and means for holding the flange against the stationary member while permitting its rotation.

7. In a machine of the kind described, a stationary member having a raceway formed in one face thereof, and a supplementary raceway comprising spaced plate-sections secured to the opposite face of the stationary member and having portions underlying the stationary member, and provided with

rivet-guiding grooves out of register with the main raceway, the space between said plate-sections being variable to accommodate rivets of different sizes, a riveting plunger operating in alinement with and partly within the space between said plate-sections, and a slide movable between the

end of the stationary member and the underlying portions of the plate sections and having a rivet-guiding groove extending therethrough transversely of its length. ¹⁰

In testimony whereof I affix my signature.

EDWIN B. STIMPSON.
